W. E. WINE

CAR DOOR LOCKING DEVICE

Filed Jan. 10, 1922

Inventor:

William E. Wine,
Parker Cook

Attorney.

UNITED STATES PATENT OFFICE.

WILLIAM E. WINE, OF TOLEDO, OHIO.

CAR-DOOR-LOCKING DEVICE.

Application filed January 10, 1922. Serial No. 528,244.

To all whom it may concern:

Be it known that I, WILLIAM E. WINE, a citizen of the United States, residing at Toledo, in the county of Lucas and State of Ohio, have invented certain new and useful Improvements in Car-Door-Locking Devices, of which the following is a specification.

My invention relates to new and useful improvements in car door locking devices and has for an object to provide a locking device that is especially adapted for use on freight cars having the ordinary drop bottom doors, or on hopper cars where the hoppers and doors are angularly disposed with relation to the car floor.

As is well known to those skilled in the art, the closing of car doors of the swinging or drop type, is easily accomplished with the exception of the final closing movement, as many of the doors become distorted or warped from the hard usage incident thereto, or particles of coal or other matters become clogged between the hinged edge of the door and the frame so that it is necessary to exert relatively great pressure on the door at the last few inches of the closing movement.

I have also found in practice that it is desirable to provide a locking device wherein the door may be lifted by hand to a temporary supported partly closed position, and from which position the door may be then pried or forced into its final closed and locked position.

Another object, therefore, of the present invention is to provide brackets in each of which is pivotally mounted a hook, the brackets being rigidly secured to the sides of a hopper, while a rod is secured to the bottom of the door, which rod is provided with offset ends designed to be engaged by the hooks pivoted to the hopper sides. A lug is also disposed on each side of the car bottom, near its outer end, so that when it is desired to close the door the offset ends of the rod on the car bottom may be revolved while still engaged by the hook, which action will raise the door to its closed and locked position.

With these and other objects in view, the invention relates to certain new and novel arrangements and combination of parts as will be hereinafter more fully described and pointed out in the claims.

Referring now to the drawings showing a preferred embodiment of the invention

Fig. 1 is a side elevation of my improved locking device showing a fragmentary portion of a hopper and hopper door, the door being shown in its locked position.

Fig. 2 is a similar view, the door in this instance, however, being in a partly opened and temporarily supported position, the locking mechanism being shown in its unlocked position.

Fig. 3 is a fragmentary detail bottom plan view of one corner of the door and hopper and showing a locking device, and

Fig. 4 is a cross sectional view showing a part of the locking device on each side of the hopper and the cooperating bar or rod secured to the bottom of the door.

It is to be understood at the outset that the locking device is primarily designed for use on hopper cars but may be used on other devices having swinging or drop doors.

Referring now to the several views, there is shown a bracket 1, which is preferably triangular in shape, in which is pivoted at its upper end, a hook 2 having the rounded jaw 3. Also pivoted at another angle of the bracket 1 is the dog 4 which is provided with the outstanding lug 5, while at the opposite angle is positioned a rivet 6 which limits the swinging movement of the hook 2. The bracket 1 is preferably formed of two plates, and rivets 7 form the pivotal points for the hook 2 and the dog 4, the rivets 6 and 7 also rigidly securing the bracket 1 to the side 8 of the hopper.

One bracket is secured to each side of the hopper so as to lock the door from its opposite side as will be shortly described.

As will be noticed in Fig. 4, the edges of the hopper 8 are provided with the short inwardly extending flanges 9, while the bottom 10 of the door is provided with the upwardly extending flanges 11 which encase the edges 9 of the hopper.

Referring now to the mechanism which is secured to the door bottom 10, there is shown the bulb angle or section 12 which is securely fastened by the rivets 13, which angle or section extends transversely of the entire door bottom and on which are mounted the bearings 14, which are also securely held by the rivets 15. In these bearings is mounted the rod 16 having the offset portions 17 which rest within said bearings, while the ends 18

100

105

110

extend beyond the opposite sides of the door as clearly shown in Fig. 4.

Also riveted to the door, at its opposite sides, and adjacent the angle 12 are the lugs 19 which act as fulcrum points for a lever or stick to swing the rod 16. The position of the hooks on the side of the hopper and the position of the offset ends 18 of the rods 16 is such that the door may be raised 10 by hand until the jaws of the hooks slip under and engage the ends 18 to support the door in a temporary nearly closed position.

At this point, a rod or stick 20, as shown in Fig. 2 in dotted lines, such as carried by 15 brakemen may be placed between the lug 19 and the end 18 and the rod 16 swung so that the end 18 will assume its lowermost position as shown in Fig. 1 which will of course, force the door against the hopper to 20 tightly close the same and the dog 4 will then be jammed against the rear surface of the hook so that the door will be held tightly locked in its closed position.

To open the door the action is reversed, 25 that is the dog is forced rearwardly by hitting the lug 5 with a hammer and the stick 20 as shown in dotted lines in Fig. 2 will again be inserted between the lug 19 and the end 18 and the rod 16 revolved so that the 30 offset end 18 will assume its uppermost position as clearly shown in Fig. 2. At this point, the hook may be knocked rearwardly by hand or by a hammer or bar allowing the door to drop to its full open position.

35 In the specification, I have spoken about the lever 20 being inserted between the lug 19 and the offset end 18 and it is to be understood that this action may be performed on either side of the door.

40 From the foregoing it will be seen that I have provided a locking device which will permit the door to be raised to a temporarily supported position and from which position relatively great force may be exerted by the 45 use of a lever to force the door to its final locked and closed position, and vice versa.

The locking device is one which is exceedingly strong, easily assembled and easily operated.

50 Many slight changes might be made without in any way departing from the spirit and scope of the invention.

Having thus described the same, what I claim as new and desire to secure by Letters Patent is:

60 1. A car door locking device comprising pivoted hooks, said hooks adapted to be secured to the car body, a rod adapted to be mounted on a door, the ends of said rod to be engaged by said hooks and capable of an eccentric movement, and adapted to hold the door in a closed position when said ends are in the lowermost position in their path of movement.

65 2. In combination with a car having a

swinging door, hooks pivotally mounted on the side of the car body, a transverse member secured to the bottom of the door, a rod having offset portions mounted on said member, the ends of said rod extending beyond the free edges of the door and adapted to rest in said hooks, fulcrum means adjacent each of said hooks to allow manual rotation of said rod to elevate said door to its locked position and to rotate said rod to lower and partly open said door.

3. A car door locking device in combination with a hopper car, brackets secured to the opposite sides of a hopper, and each of said brackets provided with a pivotally mounted hook, a transverse plate secured to the bottom of the hopper door, a rod having offset portions, brackets encasing said offset portions, and said brackets secured to said transverse plate, the ends of said rod extending beyond the opposite sides of said doors and adapted to be engaged by said hooks, means secured to said door to provide fulcrum points so that the said rod may be partially revolved to force the ends of said rod downwardly to thereby raise the door to its closed position and said fulcrum means also providing a point for forcing the ends of said rod upwardly to lower the door to a temporary supporting position.

4. In combination with a hopper car, a door locking device comprising brackets secured to the opposite sides of a hopper, a hook pivotally mounted in each of the said brackets, and a dog mounted to the rear of each of said hooks, a transverse plate secured to the door bottom, brackets secured to said transverse member and a rod provided with offset portions, said offset portions partially rotatably supported in said brackets, the ends of said rod extending beyond the sides of the door and adapted to be engaged by said hooks, outstanding means secured to each side of said door to provide fulcrum points for the reception of a lever to partially rotate said rod to thereby force the door upwardly to a closed position and to partially rotate said rod in the opposite direction to lower said door.

5. In combination with a hopper car, a door locking device comprising brackets each of which is provided with a pivoted hook, an angle iron secured to the bottom of said door, and a rod mounted on said angle iron and capable of partial rotation, the ends of said rod extending beyond the free sides of the door and engaged by said hooks, and the ends of said rod having an eccentric movement with relation to said hooks, lugs secured adjacent the said ends for providing fulcrum points to permit partial rotation of the rod secured to the door to force the ends downwardly and the door to its closed position and to permit partial rotation of the rod in the opposite

direction to lower the door to a temporary position, and means for holding the hooks in their locked positions.

6. In combination with a hopper car, having the edges of the hopper flanged inwardly and the door of the hopper having upwardly extending flanges to encase the aforesaid flanges, a locking device secured to each side of the hopper comprising a bracket having a pivotally mounted hook therein, a member extending transversely of the bottom of the door and a rod mounted on said member capable of a partial rotative movement, the ends of said rod extending beyond the sides of the door and adapted to be engaged with said hooks when in a temporary and locked position, lugs secured to the car bottom to provide fulcrum points for a lever, for partially rotating the rod secured to the bottom of the door while the ends thereof are supported by the hooks to thereby force said door upwardly to its locked position and to partially rotate said rod in the opposite direction to lower the door to a temporary supported position.

7. In a door mechanism for railway cars, the combination with a door hinged to the car body, of a pivoted member and a rotat-

able member, one carried by the car body and the other by the door, the said members being interengageably arranged to hold the door in locked position, the rotatable member being formed with its engaging portion somewhat removed from its axis of rotation, so that means may be inserted between the rotatable member and another portion of the car for forcibly rotating the said member.

8. In a door mechanism for railway cars, the combination with a door hinged to the body of the car of a pivoted member and a rotatable member, one carried by the car body and the other by the door, the rotatable member being arranged with a locking portion removed from the axis of rotation, the pivoted member having means for locking engagement with the said locking portion of the rotatable member, and said rotatable member being adapted while in door-supporting relation to said pivoted member to be rotated so as to move said door to final closed position.

In testimony whereof I affix my signature.

WILLIAM E. WINE.
